DESIGN FOR A CIGARETTE RECEPTACLE

Thomas E. Hynek, Glendale, Ariz.

Application September 5, 1939, Serial No. 87,047

Term of patent 7 years

To all whom it may concern:

Be it known that I, Thomas E. Hynek, a citizen of the United States, residing at Glendale, in the State of Arizona, have invented a new, original, and ornamental Design for Cigarette Receptacles, of which the following is a specification, reference being had to the accompanying drawing, forming part thereof.

I claim:

The ornamental design for a cigarette receptacle, as shown.

THOMAS E. HYNEK.
